CLAIM

The ornamental design for a handheld device, as shown and described.

DESCRIPTION

FIG. 1 is a front, left, and bottom perspective view of a handheld device embodying the new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a bottom plan view thereof; and,

FIG. 8 is a top plan view thereof.

The broken lines in the figures are shown for the purpose of illustrating portions of the handheld device and/or environmental matter and form no part of the claimed design.

1 Claim, 7 Drawing Sheets
